UNITED STATES PATENT OFFICE.

PHILIP HAUCK, OF PHILADELPHIA, PENNSYLVANIA.

REEL FOR WIRE.

SPECIFICATION forming part of Letters Patent No. 512,028, dated January 2, 1894.

Application filed February 23, 1892. Serial No. 422,399. (Model.)

To all whom it may concern:

Be it known that I, PHILIP HAUCK, a citizen of the United States, residing at Philadelphia, in the county of Philadelphia and State 5 of Pennsylvania, have invented certain new and useful Improvements in Wire-Reels for Wire-Stretching Machinery, of which the following is a specification.

My invention has relation to reels for wire, particularly that used in stapling books, pamphlets, &c., and in fastening the corners of paper-boxes. As is well known, the wire employed for these purposes is quite stiff and, to a considerable extent, resilient, is wound 15 into the usual rolls and secured in such condition through the medium of tie-wires. Now, owing to the unmanageability of this wire when unconfined, the removal of said tie-wires, before the roll is secured in the reel, 20 has proven inexpedient, because of the resultant loosening of the coils and the consequent snarling and buckling of the wire, seriously impairing, if not destroying, its usefulness and entailing the exercise of considerable 25 ingenuity and loss of time in the endeavor to straighten out the complication. While the restoration of the roll to its original condition, without again subjecting the wire to the coiling operation, is, ordinarily, 30 an impossibility. At the same time, where the sides of the roll of wire are closely embraced, in order to keep the coils in place and said roll in proper shape in the ordinary form of reel, the tie-wires are tightly held between 35 the sides of the latter and the roll, preventing their withdrawal. While, if clearance be left to permit of the removal of the tie-wires, the coils will become loosened, after such removal, and drop into the space left by said 40 tie-wires and, eventually, project over the sides of the reel, where the wire is liable to become tangled up with other parts of the machinery with which the reel is connected.

My invention contemplates the obviation 45 of all these difficulties by the provision of a reel adapted for reception of and embracing the sides of a roll of wire, tie-wires and all, and permitting of the removal of the tie-wires therefrom without the grasp of the sides of 50 the reel upon said roll being released. Such invention consists of a base-plate having radial ribs on its inner side and provided with

a central hollow hub, the latter having radial wings which form a core or center for the roll of wire, and, at their ends, afford a base or 55 rest for a similarly ribbed removable cap-plate. Said hub is also provided with lugs or projections whose innermost edges are outside the plane of the cap-plate, the central opening in this plate being of such shape as 60 to permit of its clearing the lugs or projections and encircling the hub, and being kept, normally, in line with the latter through the engagement of lugs, on such plate, with cer- 65 tain of said wings; also, in the provision of a cam-faced nut, having an opening similar to that of the plate last mentioned and for a like purpose, adapted to be interposed be- 70 tween the cap-plate and said projections and turned into wedging relation therewith, caus- 75 ing the impact of said ribs, only, on the sides of the roll of wire; the intervening spaces permitting of the ready removal of the tie-wires therefrom and the pressure of the ribs preventing the unnecessary loosening of the 80 coils of wire and the consequence thereof, dispensing with the necessity for closing up the space between the sides of the reel, or the provision of separate means for confining the 85 coils of wire within such reel; while the pro- 90 vision of a device for retarding the motion of the reel, when in operation, avoids the unreeling of said wire to an extent greater than is re- 95 quired.

Figure 1 is a face view and Fig. 2 an edge view of my invention complete and in position for operation. Fig. 3 is a face view of the improved reel, showing the cap removed, and Fig. 4 is a rear view of said cap. Fig. 5 is a face view of the lock-nut and the span- 90 ner or wrench therefor. Figs. 6 and 7 are perspective views of the face and under side, 95 respectively, of the lock-nut.

In said drawings, A represents the shaft or spindle which we will suppose to be in 95 the proper position relatively to the machine upon which the stitching or other operation is to be accomplished, and B the base-plate or back of the reel, the same abutting against the shoulder *a* of said shaft and having integral therewith the central boss or hub *b*, the latter being provided with the opening *b'* for reception of said shaft, and having on its outer end the lateral projections *b²* *b³*. The

radial wings b^4 , integral with said hub and plate, form a core for the coil or roll C of wire.

D is a removable cap-plate or disk having therein a circular opening d provided with 5 lateral extensions d' of a shape corresponding with, and for the purpose of permitting the cap to pass over, the projections $b^2 b^3$ and, at its center, encircle the shaft A. Said cap-plate is provided, on its inner side, with the lugs 10 d^2 , which engage with those of the wings b^4 which are in alignment with the projections $b^2 b^3$, serving to keep the opening d opposite said projections, where it is in position to permit of the ready removal of the cap, when 15 necessary, without necessitating the turning of the same for such purpose.

As will be observed, the cap D is provided with spokes d^8 , as is also the plate B, the portions between such spokes having been 20 removed for purposes of lightness, while said cap and plate have on their inner sides the ribs $b^6 d^5$, the latter being formed on the insides of said spokes and abutting against the sides of the coil or roll C, when the same is 25 placed on the arms b^4 or core as shown in Fig. 2, said coil or roll being arranged in the reel in such manner as to permit of its tie-wires c occupying the intermediate spaces between certain of said ribs. The cap D having 30 been placed in position, after the coil or roll, the lock-nut E, provided with the semi-circular cam-faced shoulders $e e'$, is next brought into use, such nut having therein a central opening e^2 , provided with extensions 35 e^5 , similar to the opening d in said cap, which opening and extensions permit of said nut being passed over the projections $b^2 b^3$ and encircling the shaft A and being brought, at its under side, into contact with the face of 40 the cap. In this position the lowermost portions of said shoulders are below the plane of the under sides of said projections, whereupon said nut is turned,—through the medium of the spanner F, or other device, which 45 grasps one of the lugs e^8 of the nut,—until the stops e^4 meet the projections $b^2 b^3$, the highest portions of the shoulders $e e'$ being thus forced, wedge-like, under said projections and a jamming action exerted on the 50 cap D by the nut E, said cap being thereby locked rigidly in the position hereinbefore described and the ribs $b^6 d^5$ caused to bear tightly on the sides of the roll of wire, thus firmly securing the latter in the reel. The 55 reel is now placed on the shaft A and the retainer G in a like position, the latter being secured by the thumb-screw g in such manner as to cause the free ends of the curved springs $g' g^2$, which latter are 60 cured in recesses in the arms $g^3 g^4$ of the retainer, to exert a gentle pressure on the cap D, such pressure being only sufficient to prevent the undesired rotation of the reel, under the momentum resulting from its rotation, 65 when the drawing of wire therefrom has ceased, without retarding such rotation when

said reel is in operation. The retainer G, at the same time, serves to keep the reel on the shaft and against the shoulder a thereon. The tie-wires c , of the coil or roll C, may now 70 be removed, the spaces between the ribs $b^6 d^5$ affording clearance therefor and allowing of their free passage, and the free end of the reeled wire led into operative relation with the stapling devices or machine, in which 75 such wire is to be used, without the danger of any other part of the roll, or the coils thereof, unwinding, whereupon the manufacture of the books, pamphlets, paper-boxes, or other operation, &c., proceeds in the ordinary or 80 any preferred manner.

What I claim as my invention is as follows:

1. In a wire-reel, the combination of a base-plate; a central hub; and a removable disk, 85 said plate and disk having on their opposite sides radial ribs adapted to be brought into clamping relation with the sides of the roll of wire, the spaces between said ribs affording clearance for the removal thereafter of the 90 tire-wires from such roll, substantially as and for the purpose specified.

2. In a wire-reel, the combination of a removable disk, a base plate; a central hub provided with lateral projections normally 95 outside the plane of said disk; and a lock-nut having a central opening provided with lateral extensions which permit of its passing said projections and encircling the hub, said nut being also provided with cam-shoulders 100 for engagement with the projections and adapted for interposition between the same and the disk, exerting a wedge-like action on the latter, substantially as and for the purpose specified.

3. In a reel, the combination of a base-plate, a central boss or hub having lateral projections, a removable disk on said boss or hub, and a lock-nut intermediate the disk and projections, substantially as and for the purpose specified.

4. In a wire-reel, the combination of a base-plate having integral therewith a central hub; radial wings integral with the latter and forming a core for the roll of wire; and a removable disk, said plate and disk having on their opposite sides radial ribs adapted to be brought into clamping relation with the sides of the roll, the spaces between said ribs affording clearance for the removal thereafter 115 of the tie-wires from said roll, substantially as and for the purpose specified.

5. In a wire-reel, the combination of a base-plate; a central hub provided with lateral projections; a removable disk having a central opening provided with lateral extensions, permitting it to clear said projections and encircle the hub; and a lock-nut provided with an opening similar to that of said disk and for a like purpose and having cam-shoulders 125 for engagement with the projections and adapted for interposition between the same 130

and the disk, exerting a wedge-like action on the latter, substantially as and for the purpose specified.

6. In a wire-reel, the combination of a removable disk; a base-plate; a central hub provided with lateral projections; a lock-nut having a central opening with lateral extensions, which permit of its passing the projections and encircling the hub, and provided with cam-shoulders having limiting stops, for engagement with the projections, said nut be-

ing adapted for interposition between the latter and the disk and having lugs for facilitating its operation, substantially as and for the purpose specified.

In testimony whereof I have hereunto set my hand this 19th day of February, A.D. 1891.

PHILIP HAUCK.
